(57) **CLAIM**

The ornamental design for a gimbal tripod, as shown and described.

DESCRIPTION

FIG. 1 is a front perspective view of a gimbal tripod showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a partial enlarged view of FIG. 1;

FIG. 9 is an enlarged partial view of FIG. 2;

FIG. 10 is an enlarged partial view of FIG. 3;

FIG. 11 is an enlarged partial view of FIG. 4;

FIG. 12 is an enlarged partial view of FIG. 5;

FIG. 13 is an enlarged partial view of FIG. 6;

FIG. 14 is an enlarged partial view of FIG. 7;

FIG. 15 is front perspective view showing the gimbal tripod in the second state; and,

FIG. 16 is front perspective view showing the gimbal tripod in the third state.

The broken lines in the figures are for the purposes of illustrating portions of the gimbal tripod, which form no part of the claim design.

The dash-dot-dash lines are for an notating enlarged views, which form no part of the claim design.

1 Claim, 16 Drawing Sheets
